WATER EVACUATION SYSTEM IN
TANGENTIAL DRIERSArthur Williams, Munster, Ind., assignor to The
Superheater Company, New York, N. Y.

Application June 11, 1943, Serial No. 490,410

3 Claims. (Cl. 122—491)

The present invention relates to improvements in steam and water separators and particularly to means for insuring the efficient discharge from the separator and the disposal of water that is separated from the steam.

One type of steam and water separator is sometimes known as a "tangential drier." This apparatus is commonly employed in connection with locomotive boilers for separating water before the steam passes through the dry pipe to the superheater and engines of a locomotive. The tangential drier is mounted upon the upturned end of the dry pipe in the steam dome and consists of a casing open at its top to provide a steam inlet and containing a series of vanes which give the steam and water mixture a whirling motion within the casing causing the water to be thrown off against its walls while the steam passes through the dry pipe to the superheater. The water runs down into a chamber in the lower part of the drier from which it is discharged.

In accordance with the present invention a drier of this type has its outlets connected to discharge into a receptacle located outside the boiler from which under normal conditions of operation the separated water is bled off. The water may pass into a steam line supplying auxiliary steam consumers so that the water from the separator is flashed into steam and returned to use and the heat conserved. When unusual amounts of water are carried over and pass from the separator into the receptacle, the rising water makes contact with an electrode arranged to open a valve in another and larger discharge line from the receptacle.

In the drawings:

Figure 1 is a diagrammatic view of a locomotive boiler equipped with a steam and water separating system embodying the present invention; and

Figure 2 is an enlarged view of the water collecting chamber and control valve.

The locomotive boiler is provided with the usual steam dome 10 from which a dry pipe 11 extends forwardly to the superheater and throttle and thence to the engines. The dry pipe 11 has an upturned end portion on which is mounted a steam and water separator 12 of the type known, because of its action, as a "tangential drier." Such a drier is shown in my earlier Patent 2,122,630, dated July 5, 1938. In the operation of the boiler the steam and water mixture enters the drier through an inlet 13 at its top and a whirling motion is imparted thereto. Centrifugal action causes the water to be thrown off

tangentially against the wall of the drier casing so that it runs down into a chamber 16 having several outlets that ordinarily discharge the water back into the steam space of the boiler.

In accordance with the present invention an outlet 17 from the chamber 16 is connected by a pipe 20 to a chamber or receptacle 21 located outside of the boiler. Water entering the receptacle 21 passes by way of a restricted bleed pipe 22 having a choke 23 therein into a steam line 24 subject to the control valve 25 leading from the steam turret in the cab to supply steam at lower than full boiler pressure to auxiliary steam consumers such as the stoker jets 26. Also connected with the receptacle 21 is a discharge conduit 27 of larger capacity than the pipe 22 having a normally closed valve 28 therein. A muffler 29 may be interposed in conduit 27 beyond valve 28. Extending into the receptacle 21 is an electrode 30 having its inner end so located that when a predetermined amount of water accumulates in the receptacle the electrode is contacted thereby to complete an electrical circuit and cause energization through relay 31 of a valve operating solenoid 36 to open a valve 32 in an air line 33 leading from the air reservoir 34 to an air motor whose piston 35 (Fig. 2) is connected to open the valve 28 and thus permit the receptacle 21 and muffler 29 to be discharged immediately.

In normal operation the water separated from the steam in the drier 12 passes through the pipe 20 into the receptacle 21 and from the latter via choke 23 and pipe 22 into the auxiliary steam line 24 where it flashes into steam due to the lower pressure normally maintained in this pipe and is thus disposed of. When such conditions prevail in the operation of the boiler as would cause excessively large amounts of water to be carried over into the drier 12 the water flowing from separating chamber 16 through pipe 20 into the receptacle 21 is in greater quantity than may be rapidly discharged through the choke 23 in pipe 22 and consequently rises to contact the electrode 30, thereupon through the intermediary of the control apparatus described, the valve 28 in the discharge conduit 27 is opened so that the unusual large amount or volume of water may be immediately discharged from the receptacle 21 through conduit 27.

It should be noted that the bleed-off pipe 22 connecting into the water discharge conduit 20, 27 for the drier 12 acts to speed up the opening of the discharge valve 28 when excessive quantities of water enter the drier. The discharge

valve 28 being normally closed forms a dead end at the end of the section 20 of the water discharge conduit. With the bleed-off pipe 22 located close to the position of the valve 28 in the conduit 20, 27 and adjacent the valve control electrode 30 a constant flow of steam with or without small amounts of moisture is maintained throughout section 20 of the water discharge conduit. This keeps the pipe 20 and the body of valve 28 free of air and establishes a lower pressure at the location of the electrode 30 than exists in the drier so that when there is an excessive amount of water to be discharged it flows immediately to the valve control electrode 30 and produces prompt opening of the valve 28.

What I claim is:

1. In a boiler equipped with a steam and water separator mounted within the steam space and having a chamber for receiving water separated from the steam and one or more outlets for discharging the separated water; a receptacle so connected with said outlets as to receive the separated water therefrom; a restricted bleed pipe connected to said receptacle for discharging water therefrom into a region of lower than boiler pressure; a second water discharge conduit connecting the said receptacle with a low pressure region, a normally closed valve in said conduit; means for opening said valve; and means responsive to accumulation of a predetermined amount of water in said receptacle for causing actuation of said valve opening means to effect opening of said valve.

2. In a boiler equipped with a steam and water separator mounted within the steam space and having an outlet for discharging the separated water; a water discharge conduit connecting said outlet with a region of lower than boiler pressure;

a normally closed valve in said conduit; means forming a collecting chamber in said conduit between said separator outlet and said valve; means associated with said chamber for causing opening of said valve upon accumulation of a predetermined amount of water in said chamber; and a restricted bleed-off pipe connected into said conduit closely adjacent to said chamber and discharging into a region of lower than boiler pressure for continuously withdrawing small amounts of steam and water from said conduit so as to maintain said chamber conditioned to receive fluid in amounts at least corresponding to the predetermined amount causing opening of said valve for effecting quick opening of the latter upon discharge of relatively larger amounts of water from said separator.

3. In a boiler equipped with a steam and water separator mounted within the steam space and having an outlet for discharging the separated water; a water discharge conduit connected to said outlet and discharging into a region of lower than boiler pressure; a normally closed valve in said conduit; means associated with said conduit for causing opening of said valve upon flow of a predetermined volume of water through said conduit; and a restricted bleed-off pipe connected to said conduit between said separator outlet and said valve and closely adjacent to the latter, said bleed-off pipe discharging into a region of low pressure for continuously maintaining flow through said conduit so as to maintain the latter conditioned to receive fluid in amounts at least corresponding to the predetermined amount causing opening of said valve for effecting quick opening of the latter upon discharge of relatively larger amounts of water from said separator.

ARTHUR WILLIAMS.
